HENRY L. DICKENSON, OF EAST BERLIN, CONNECTICUT.

Letters Patent No. 64,752, dated May 14, 1867.

IMPROVED MEASURE AND FUNNEL COMBINED.

The Schedule referred to in these Letters Patent and making part of the same.

TO ALL WHOM IT MAY CONCERN:

Be it known that I, HENRY L. DICKENSON, of East Berlin, county of Hartford, and State of Connecticut, have invented a certain new and useful Improvement in Combined Liquor Measure and Funnel; and to enable others skilled in the art to make and use the same, I will proceed to describe it, referring to the drawings, in which the same letters indicate like parts in each of the figures.

Vessels for measuring liquors are usually made of various sizes, as pint, quart, gallon, &c. The required quantity wanted is usually drawn in a measure of suitable capacity therefor, and poured therefrom through a tunnel into a jug or other vessel. By the use of this improvement the liquor may be drawn into a graduated measure, having a tunnel valve nozzle attached to the under side of the measure, so that by simply placing said nozzle into the neck of the jug, and slightly pressing the measure down, the valve will open and allow the liquor to flow freely from the measure into said jug.

In the accompanying drawings, A is a measure, which may be made of any given capacity, and with rings or other marks formed on the body thereof to indicate various quantities to be drawn or measured therein. B is the bottom of said measure, which is made dishing. C is a nozzle, secured to the under side and to the centre of said dishing bottom. C' is a sleeve, the inside of which is made larger than the outside of the nozzle C, the object of which is to form an air passage between C and C'. The sleeve C' is provided with a collar, D. Between this collar D and bottom B, over the nozzle C, is arranged a spring, E, the office of which is to press the flange or collar D downward from the bottom B. F is a valve-rod, which passes up through the nozzle C, and is secured to the valve G, the lower end of which is secured to the sleeve C', by means of which, in connection with the action of the spring E, the valve G is compressed upon the upper end of the nozzle C.

Now, it will be clearly seen that when a given quantity of liquor has been drawn in this measure, by simply placing its sleeve C' into the orifice of a jug or other vessel, and pressing down, the spring will yield to the pressure, and the valve will be lifted, so that the liquor may flow freely from said measure into the jug. It will be further noticeable that as the liquor is flowing from said measure into a jug, the space between the nozzle C and the sleeve C' affords a passage for the escape of air from the jug or vessel. H are supports, secured to the lower end of the measure, for the purpose of protecting the nozzle from injury. I is a handle, made and secured to the measure in the usual way.

I believe I have thus shown the nature, construction, and advantage of this improvement, so as to enable others skilled to make and use the same therefrom.

What I claim therefor, and desire to secure by Letters Patent, is—

The combination of the measure A and nozzle C with the valve G, sleeve C', and spring E, substantially as and for the purpose described.

HENRY L. DICKENSON. [L. S.]
